CONTAINER LID

Herbert Roesinger, Cleveland, Ohio

Application December 8, 1936, Serial No. 114,783

5 Claims. (Cl. 248—147)

This invention relates broadly to containers, and more specifically to improvements in mechanism for raising and lowering the cover thereon.

One of the objects of the invention is to provide a cover actuating mechanism adapted, by the exercise of manual effort, to effect the closure of the container, and adapted to effect the removal of the cover through the energy of a spring wound while the cover is being actuated to its closed adjustment.

Another object of the invention is to provide a container cover actuating mechanism constructed to tightly seal and rigidly support the container when the cover is engaged therewith.

Another object of the invention is to provide a supporting structure and closure mechanism for a container which will maintain the cover in place in the event the container is accidentally overturned or upset by prowling animals.

Another object of the invention is to construct an actuating mechanism which will elevate the cover from the container upon release of a light acting trigger requiring the use of but one hand of the operator.

Another object of the invention is the provision of a crank arm for actuating the cover when the operating mechanism therefor is adjusted in its elevated position and extended beyond reach of an individual or child wishing to operate the cover closing device.

Other objects and advantages more or less ancillary of the foregoing and the manner in which all the various objects are realized will appear in the following description which, considered in connection with the accompanying drawing, sets forth the preferred embodiment of the invention.

Referring to the drawing:

Fig. 1 is a front elevational view of a container disposed within the improved supporting frame, and including the cover and operating mechanism therefor; portions of the frame and cover being broken away and shown in section in the interest of clarity;

Fig. 2 is a side elevational view of the apparatus shown in Fig. 1, a portion of the frame being broken away and a portion of the cover being shown in section;

Fig. 3 is a detail plan view partially in section of the cover actuating mechanism, the drawing being shown upon an enlarged scale;

Fig. 4 is a sectional view of the cover actuating device illustrating a modification of the elevating mechanism shown in Fig. 2.

As illustrated in Figs. 1 and 2, the container

10, which by way of example may be a refuse pail, is positioned within a housing 11 which comprises a cylindrical body or frame formed with an opening 12 in the forward face thereof. Upon the top of the housing 11 there is a bearing bracket or bushing 13 having a rectangular opening therein for guiding a plunger rack 14. The lower portion of the rack is formed with a spherical head 15 having a cup 16 engaged therewith to effect universal movement or a swivel connection of the cover within the rack. The cup 16 is mounted upon the container lid 17 which is preferably constructed from relatively light sheet metal pressed as shown with a laterally extended flange. Upon the lower face of the 15 cover flange there is a yieldable packing material or gasket 18 arranged to engage the peripheral edge of the container 10.

Adjacent the bushing 13 there is a bracket 19 having lugs 20 thereon apertured to receive a 20 shaft 21 keyed therein upon which there is mounted a pinion 22. Circumambient the shaft 21 there is a helical spring 24, one end of which is anchored upon a stud 23 secured in the face of the pinion, while the other end of the spring 25 is secured in a groove formed in the shaft 21. Upon the upper face of the bracket 19 there is a spring-pressed plunger 25, the lower face 26 thereof being beveled at an acute angle to permit the rotation of the gear 22 when the rack 14 30 is actuated in the direction which effects the removal of the cover. The upper face of the plunger 25 is machined parallel to the face of the pinion teeth, the structure constituting a ratchet to prevent rotation of the gear when the 35 rack 14 is actuated to effect the engagement of the cover with the container. The top of the rack 14 is formed with a head or button 27 to accommodate manipulation of the rack into engagement with the top of the container.

As shown in the modified form illustrated in Fig. 4, the shaft 21 is journaled in one of the lugs 20, the outer end thereof being extended for the reception of a crank arm 28 loosely journalled thereon and retained from longitudinal separation from the shaft by a screw 29. The hub of the crank arm 28 is formed with a diametric slot constituting jaws 30 adapted for engagement with a pin 31 pressed into a cross drilled opening in the shaft 21. Within the bore of the hub of the crank arm 28 and intermediate the end of the shaft 21, there is a compression spring 32 adapted to retract the jaws 30 from engagement with the pin 31. The inner end of the shaft 21 is 50 55

formed with a pilot bearing journalled in the bored end of a stub arbor 21a. The pinion 22 in this structure is keyed upon the shaft 21 and the stub arbor 21a is affixed within its supporting lug 20. When it is desired to use the crank arm, pressure is exerted against the arm to overcome the spring and effect engagement of the jaws 30 with the pin 31, whereupon the shaft may be rotated and the rack 14 lowered to the lid-closing position. The provision of the crank arm facilitates the operation of the closing mechanism by a child who may not be tall enough to reach the end of the plunger when the cover is in its elevated position.

15 In operation, the container cover is lowered upon the receptacle by pressing or cranking the plunger or rack 14 downwardly until the gasket 18 engages the top of the container 10, whereupon the pinion is locked from reverse rotation by the ratchet plunger 25. During this operation the rack 14 will effect rotation of the pinion 22 and thus tightly winds the spring 24 about the shaft 21. When it is desired to remove the cover, the knob 33 of the ratchet or spring-pressed plunger 25 may be moved rearwardly to disengage the teeth of the pinion 22, thus releasing the helical spring 24 which then effects the rotation of the pinion in the opposite direction and thereby elevates the rack and removes the cover 17.

Although the foregoing description is necessarily of a detailed character, in order that the invention may be completely set forth, it is to be understood that the specific terminology is not intended to be restrictive or confining, and that various rearrangements of parts and modifications of detail may be resorted to without departing from the scope or spirit of the invention as herein claimed.

40 I claim:

1. In combination with a container, a cover actuating mechanism therefor comprising a supporting frame having an opening in the side wall thereof for the admission of a container, a reciprocative rack supported by said frame, a container cover mounted on said rack and adapted for engagement with the upper edge of said container, a pinion engaged with said rack, a helical spring mounted on said pinion and adapted to be wound upon rotation of said pinion and a ratchet engaged with said pinion for retaining said rack in cover-closing position upon said container.

2. In combination with a container, a cover actuating mechanism therefor comprising a supporting structure for the reception of said container, a reciprocative rack mounted thereon, a cover mounted on said rack and engageable with said container, a pinion engaged with said rack, a spring co-ordinated with said pinion and adapted to be wound upon rotation of said pinion and a spring-pressed plunger engageable with said pinion for restraining rotation of said pinion when said spring is wound.

3. In combination with a container, a cover actuating mechanism therefor comprising a frame having an opening in the side wall thereof for the reception of said container, a reciprocative rack mounted on said frame, a cover swivelably mounted on said rack, a yieldable packing material mounted on said cover and engageable with said container, a pinion intergeared with said rack, a helical spring having one end thereof connected to said pinion and the other end anchored against rotation, and a ratchet co-ordinated with said pinion for restraining the rotative movement of said pinion in one direction.

4. A cover actuating mechanism for a container comprising a cover arranged for abutting engagement with the top of a container, a plunger for raising and lowering said cover, a rotative member driven by said plunger, a coiled spring adapted to be wound by the rotative member upon depression of said plunger, and a ratchet engaged with said rotative member and arranged to restrain upward movement of said plunger when said spring is wound.

5. In combination with a container, a cover actuating mechanism therefor comprising a frame having an opening in the side wall thereof for the reception of said container, a reciprocative rack mounted on said frame, a cover swivelably mounted on said rack, a yieldable packing material mounted on said cover and engageable with said container, a pinion intergeared with said rack, a helical spring having one end thereof connected to said pinion and the other end anchored against rotation, a ratchet co-ordinated with said pinion for restraining the rotative movement of said pinion in one direction and a crank arm detachably engageable with said pinion for lowering said rack.

HERBERT ROESINGER.
